FIG. 1

FIG. 2

FIG. 3

FIGURE 1 is a perspective view of my new design;
FIGURE 2 is an end view of the design, both ends
thereof being the same; and

FIGURE 3 is a view of the design taken from the
bottom of the blower unit when oriented as in FIG-
URE 1.

The dominant features of my design reside in the portions shown in full lines.

I claim:

The ornamental design for an air pump, as shown and described.
